UNITED STATES PATENT OFFICE.

GEORGE GRISEL AND EARL K. COOLEY, OF SAN FRANCISCO, CALIFORNIA.

BOTTLE-COVER.

SPECIFICATION forming part of Letters Patent No. 248,307, dated October 18, 1881.

Application filed August 12, 1881. (No model.)

To all whom it may concern:

Be it known that we, GEORGE GRISEL and EARL K. COOLEY, of the city and county of San Francisco, State of California, have invented certain new and useful Improvements in Bottle-Covers; and we do hereby declare that the following is a full, clear, and exact description thereof, reference being had to the accompanying drawings.

10 We make our sheath or cover tapering in form, of lengths of straw or other stalk, so arranged as that they shall present one thickness at the large end and two thicknesses at the small end.

15 The invention will be understood as herein-after set forth.

Referring to the accompanying drawings, Figure 1 is a perspective view of the bottle-cover. Fig. 2 is a view looking into the large 20 end. Fig. 3 is a section through *x y*, Fig. 1.

25 A is a sheath or cover for bottles, which can be made of tule-straw, (*Scirpus lacustris*), grain-straw, or other suitable weed or stalk. We prefer the tule-straw because of its soft spongy character.

In making our sheath or cover, we cut the straws or stalks a little longer than the bottle. We then place them side by side on a tapering cylindrical form and sew them together by 30 three rows of stitches. We sew one row of stitches near each end of the cover, and another at its middle. Any of the ordinary styles of stitches can be employed, but we prefer the lock-stitch, which is made with a single thread.

At the large end of the sheath or cover the straws or stalks will lie loosely side by side, and in sewing them together a stitch will pass through the middle of each stalk; but we do not confine ourselves to the exact fact of stitching each straw or stalk in this row, because this row of stitches is not so important as the end rows, and in some cases it might be dispensed with entirely. At the opposite or small end of the cover the diminished size of the form 45 will cause the straws or stalks to overlap, so that one will lie upon another, and thus provide a double thickness at this end.

The cover, when removed from the form, will be a hollow tapering cone open at both ends 50 and united by three rows of stitches.

Having thus described our invention, what we claim, and desire to secure by Letters Patent, is—

A tapering sheath for bottles, open at both 55 ends and formed of lengths of straw or other stalk, each length running the full length of the sheath, and so arranged as to be one thickness of stalk at the large end, and two thicknesses at the small end, and sewed together, 60 substantially as set forth.

In witness whereof we have hereunto set our hands and seals.

GEORGE GRISEL. [L. S.]
EARL K. COOLEY. [L. S.]
